UNITED STATES PATENT OFFICE

2,370,448

CIRCUIT BREAKER

Thomas M. Cole, New York, N. Y., assignor to
 Federal Electric Products Company, Inc., Newark, N. J., a corporation of New Jersey

Application January 30, 1942, Serial No. 428,880

8 Claims. (Cl. 200—116)

This invention relates to circuit breakers and, more particularly, to circuit breakers of the type disclosed in United States Letters Patent No. 2,242,717, granted upon an application filed by me and Christopher I. Smith. This application is a continuation in part of my application Serial No. 412,356, filed September 25, 1941, Patent No. 2,362,051.

One object of the present invention is the provision in a circuit breaker of the above indicated type of means for facilitating the adjustment of the thermostatic device which controls the tripping of the breaker to open condition pursuant to the occurrence of an overload.

Another object of the invention is the provision of an improved assembly unit comprising the operating member and the companion contact members which are carried by or secured thereto, whereby to facilitate the assembly of these parts as a unit in the casing of the circuit breaker and with the other parts thereof.

Another object of the invention is the provision of a casing of improved construction and having arc chutes formed as integral parts of said casing.

The above and other objects, features and advantages of the invention will be more particularly described in the following specification and pointed out in the claims, and for a more complete understanding thereof reference is to be had to the accompanying drawings in which, for the purpose of illustration, the presently preferred embodiment of the invention is shown.

In the drawings:

Fig. 1 is a perspective view of a circuit breaker embodying the present invention;

Fig. 2 is a side view of the circuit breaker, with the casing cover removed, showing the breaker in manually opened condition;

Fig. 3 is a bottom view of the circuit breaker;

Fig. 4 is a view similar to Fig. 2 showing the circuit breaker closed;

Fig. 5 is a view similar to Fig. 2 showing the tripped condition of the circuit breaker;

Fig. 6 is an end view of the circuit breaker;

Fig. 7 is a sectional view of part of the circuit breaker on the line 7—7 of Fig. 8;

Fig. 8 is a cross sectional view on the line 8—8 of Fig. 1;

Fig. 9 is a side view of the casing itself, the cover being removed;

Fig. 10 is a view partly in section and partly in elevation on the line 10—10 of Fig. 4.

Referring now to the drawings in detail, the circuit breaker embodying the present invention comprises a casing 10 preferably molded in one part of "Bakelite" or other suitable insulation material. The walls of said casing define a chamber in which the several operating parts of the breaker are positioned, and said casing is

provided with a removable cover 12 preferably molded of "Bakelite" or similar material. Said chamber is defined by a side wall 14, end walls 16 and 18, a top wall 20, and a bottom wall 22. Top wall 20 has integral spaced parts 24 and 26 which project laterally of the casing beyond the edges 28 and 30 of end walls 16 and 18, respectively, the free ends 32 of said parts 24 and 26 projecting to the plane of the outer edge portions 34 of bottom wall 22. Said casing is provided with thickened portions 36, 38, 40, 42 and 44 provided with holes extending therethrough for bolts or the like 46 by which said cover 12 is removably secured in position. When cover 12 is fastened in position the inner surface thereof engages the edges 28 and 30 of end walls 16 and 18, the edges of top wall 20 below parts 24 and 26, and the thickened portions 40, 42 and 44 adjacent bottom wall 22, and the outer surface of cover 12 is preferably flush with the edges of parts 24, 26 and 34. Said cover has a lower projecting end portion 48 which fits in a recess 50 in the bottom wall 22 and which projects beyond said bottom wall to the plane of integral parts 52 and 54 on bottom wall 22. Cover 12 has an upper intermediate portion 56 which projects within the recess formed between the confronting edges of parts 24 and 26, and rear wall 14 of the casing has an upper intermediate portion 58 which confronts said part 56 of cover 12. Parts 56, 58 and the confronting edges of parts 24 and 26 define an opening 60 in the top wall of the casing for the knob 62 of the switch operating member 64 which will presently be more specifically described.

Said switch operating member 64 is molded or otherwise made of insulation material, for example, "Bakelite," and is pivotally mounted in the casing preferably in the manner hereinafter to be detailed. Said switch operating member 64 comprises a body portion 66 having an arcuate segmental portion 68 which extends preferably for the full width of the casing and closes opening 60 through which knob 62 projects, in all positions of said knob. A contact member 70 is mounted in fixed relation to operating member 64, being carried by a metal plate or bracket 72 secured to body portion 66 of operating member 64 by a screw 74. An edge of plate 72 abuts a raised portion 75 on member 64. The companion contact member 76 is fixed to a metal arm 78 carried by operating member 64 and pivotally mounted thereon. More particularly, arm 78 is pivotally mounted at its intermediate part 80 on the circular shank portion 82 of a pin 84 in position between a boss 86 formed on body portion 66 of operating member 64 and the head 88 of said pin. A part 90 of the stem of pin 84 is knurled and fits with a forced fit into the axial opening 92 of body portion 66, as shown in Fig. 8.

thus fixedly securing said pin to said operating member in said opening. Part 82 of the pin is larger than the rest of the shank of the pin and forms a shoulder 93 which engages boss 86 to limit the movement of the pin into said opening 92 when the pin is entered into said opening. The end portion 93a of said pin is preferably smooth and somewhat smaller in diameter than opening 92 to facilitate mounting of the pin. When shoulder 93 is adjacent boss 86, the space between said boss and the confronting surface of the head of the pin is but slightly wider than the thickness of the adjacent part of arm 80, so that movement of said arm axially of member 64 is prevented and contact members 70 and 76 are held in properly aligned positions.

A circular hub portion or trunnion 94 is formed on operating member 64 and is journaled in cylindrical recess 96 formed in the inner surface of casing wall 14. The head 88 of pin 84 is circular and is journaled in a cylindrical recess 98 provided in a boss 99 provided on the inner surface of casing cover 12, recesses 96 and 98 being in axial alignment. Thus, switch operating member 64 is pivotally mounted in the casing and arm 78 is pivotally mounted on said switch operating member, being journalled for turning movement on pin 84. Arm 78 is biased for movement in a clockwise direction (viewing Fig. 2) by a spring 100 which has an intermediate portion 102 thereof coiled around boss 86 and which has end portions 104 and 106 in engagement with arm 78 and one end of the arcuate segmental portion 68, respectively. A fibre strip 108 is secured to the body portion 66 of switch operating member 64 between the latter and bracket 72 and arm 78 and as shown in Fig. 10 is folded over the adjacent edge 110 of body portion 66 to protect the adjacent part of the latter against deterioration by heat of the arcs which might be drawn when the contact members are being separated.

As illustrated in Fig. 4, when the circuit breaker is closed arm 78 is held against movement in a clockwise direction by the thermostatic or bi-metallic strip 112 which is electrically connected to arm 78 by a flexible connecting member or pigtail 114. When an overload occurs said strip 112 is flexed laterally to the right (viewing Fig. 4) out of engagement with the adjacent end of arm 78, thus permitting spring 100 to move arm 78 in a clockwise direction for separating contact member 76 from the companion contact member 70, during which action switch operating member 64 moves from the position illustrated in Fig. 4 to the position illustrated in Fig. 5 under the action of a spring 116 which is clearly illustrated in Figs. 2, 4, 5 and 10, and which will be presently described. It will be observed that during the movement of arm 78 to switch opening position during which contact member 76 moves away from contact member 70, said last mentioned contact member 70 has a movement in a clockwise direction with switch operating member 64 as described in the above mentioned patent whereby to delay somewhat the interruption of the circuit, this being desirable in certain cases, for example, when the circuit breaker is used in alternating current circuits. It will be noted, however, that movement of contact member 70 concurrently with contact member 76 is of short duration as the movement of contact member 76 is more rapid than the movement of contact member 70 although in the same direction.

Spring 116 is V-shaped, as shown, and comprises parts 118 connected at their outer ends to an integral transverse end part 120 and at their other ends to the inner convolution 121 of laterally spaced coils 122, the outer convolutions of said coils being in integral relation with the arms 124 which terminate in inturned or transverse portions 126. End portion 120 engages body portion 66 of the switch operating member 64 in a notched part 128 of the latter and end portions 126 engage the bottom wall 22 of the casing in a notched part 130 of the thickened portion 44 of said casing. It will be noted that spring 116 is organized with switch operating member 64 and with casing 10 in such manner that the circuit breaker when manually operated is opened and closed with a snap action and it is, of course, apparent that said spring 116 holds the contact members in either their engaged or disengaged positions in the non-tripped condition of the circuit breaker. Further, as explained above, when the circuit breaker is tripped spring 116 moves switch operating member 64 from the position illustrated in Fig. 4 to the position illustrated in Fig. 5, so that the tripped condition is readily indicated by the position of knob 62 adjacent part 26 of the casing, and also so that the contact member 70 follows contact member 76 during part of the movement of the latter to its tripped condition.

An important feature of the present invention resides in the mounting of the bi-metallic strip 112 and in the provision of means for calibrating the circuit breaker for tripping thereof under a predetermined load. For these purposes bi-metallic strip 112 has an end portion 132 thereof positioned in a metal collar 134 which engages one leg 136 of an L-shaped terminal member 138. As shown more clearly in Fig. 7 collar 134 has an end wall 140 which is inclined approximately in the same direction as the part 132 of said bi-metallic strip 112, and a calibrating screw 142 is threaded through an opening 144 in said wall and engages said part 132 of the strip. Preferably, as here shown, screw 142 is at right angles to part 132 of strip 112. Thus, by adjusting said screw 142 the end portion 146 of bi-metallic strip 112 can be adjusted in relation to the free end of arm 78 so that by the flexing of the strip in response to the action of heat it disengages said arm under a predetermined load condition. It will be noted also that screw 142 holds the strip 112 in electrical engagement with leg 136 of terminal member 138 and also holds collar 134 in engagement with said terminal member.

The leg 148 of terminal member 138 is releasably secured in position on the ledge 150 formed as an integral part of casing 10 adjacent the end wall 18 thereof. Said leg 148 is releasably held in said position by a screw 152 which is passed through an opening 154 in ledge 150 and which is threaded into leg 148 of terminal member 138. An opening 156 is provided in the lateral extension of bottom wall 22 of the casing to permit insertion of screw 152, and as shown in Fig. 2 after said screw is engaged with terminal member 138 for holding the latter in position a fibre strip 158 is inserted in opening 156 for closing the latter.

A terminal connector 160 is secured to the upper surface of leg 148 of terminal member 138 on ledge 150 by said screw 152. Said terminal connector is provided with a screw 162 for securing the connecting wire (not shown) of the

circuit in said terminal connector in electrical engagement therewith thereby to electrically connect said wire to terminal 138. The terminal at the other side of the circuit breaker is constituted by a flat metal strip 164 which is connected at its inner end to bracket 72 by a flexible connector or pigtail 166. Said terminal strip 164 lies flatwise in recesses 168, 170 and 172 formed in the upper edges of wall portions 174, 176 and in end wall 16, respectively. Movement of strip 164 transversely of said wall portions is prevented by the engagement of the inner end of said strip with an edge 178 of thickened portion 44 of casing wall 22 and by the engagement of a struck out portion 180 of said strip with the wall portion 174. Said strip 164 is held in position by casing cover 12, the inner surface of said cover engaging the adjacent surface of said strip while the opposite surface of the latter is engaged with the bottoms of said recesses 168, 170 and 172.

A terminal connector 182 is connected to the outer end of terminal strip 164 by a screw 184 which engages and passes through the laterally bent portion 186 of said strip and which holds the latter clamped against the strip 188 which is fixed in the terminal connector 182. A screw 190 on terminal connector 182 serves to hold a wire (not shown) at the other side of the circuit in releasable engagement with said terminal connector.

Casing 10 is provided with arc chutes which also form passages for the exhaust of gases from the interior of the casing. Said arc chutes are formed by parts molded integrally with the casing. Thus, one arc chute is constituted by a part 192 of wall 176 and the adjacent edge of part 36 of the casing and is continuous with the passage 194 which terminates in an outlet opening 196 in end wall 16 of the casing. The other arc chute is formed between wall 174 and the confronting part of wall 176 and communicates with a passage 198 which terminates in an outlet opening 200 in the bottom wall of the casing. As illustrated in Fig. 5 the inlet end of the upper arc chute formed between parts 36 and 192 of the casing is adjacent to and in alignment with the space between separated contact members 70 and 76 in the tripped condition of the switch. On the other hand, as illustrated in Fig. 2 when the switch is manually opened the inlet end of the arc chute formed between walls 174 and 176 is adjacent the space between the separated contacts 70 and 76. In other words, the inlet end of one arc chute is adjacent the space between said contact members when they are separated under one condition of operation of the switch, and the inlet end of the other arc chute is adjacent the space between said contact members when they are separated under a different condition of operation of the switch.

The manner of assembling the several parts of the circuit breaker with the casing will be apparent from the above description of the construction and relation of the casing and the various parts of the circuit breaker. It will be noted that the operating member 64 and all of the parts carried thereby can be assembled as a unit and inserted as a unit in the casing through the open side thereof before the cover 12 is attached. Likewise, it will be understood that the assembled unit can include the thermostatic strip 112 and the terminal members 148 and 164. After the parts are inserted in the casing cover 12 is applied and fastened in position, thus completing the assembly. The circuit breaker can be mounted on any

suitable panel or support and easily fastened thereto in any suitable way, and as here shown casing 10 is provided with the above mentioned part 52 and with part 202 which has a slot 204 (Figs. 2, 3 and 9) for a fastening screw (not shown). More particularly, for securing this circuit breaker to the panel, the outer end of part 52 is engaged under a holding member with which the panel is customarily provided and the fastening screw positioned in slot 204 is threaded into an opening in the panel, the head of said screw engaging the end 205 of part 202. By reference to Fig. 3 it will be noted that slot 204 is open at the side 14 of casing 10 by reason of the fact that said casing is molded. It will be understood that when casing 10 is fastened to the panel the latter is engaged at three points by the surfaces of parts 48, 52 and 54 in abutting relation with the confronting surface portions of the panel whereby the bottom wall 22 of the casing is spaced from the confronting panel surface. Thus, a plurality of circuit breakers can be mounted on the panel in adjacent side by side relation without obstruction of opening 200 of passage 198.

While I have shown and described the preferred embodiment of my invention it will be understood that the latter may be embodied otherwise than as herein shown or illustrated, and further it will be understood that in the illustrated embodiment certain changes in the details of construction and in the arrangement of parts may be made without departing from the spirit of the invention. Therefore, I do not wish to be limited to the construction herein illustrated or described except to the extent which may be required by the scope of the appended claims.

Having thus described my invention, what I claim and desire to secure by Letters Patent is:

1. In an electric circuit breaker, relatively movable contact members engageable with and disengageable from each other, an arm mounted for pivotal movement and carrying one of said contact members, a thermostatic strip releasably engaging said arm for preventing movement thereof in one direction, a mounting member in which said strip is releasably and movably positioned, said mounting member having a wall portion substantially parallel to the adjacent face of said strip, and an adjustable member carried by said wall portion of the mounting member and releasably engageable with said adjacent face of said strip at right angles thereto for adjusting said strip in relation to said contact-carrying arm said strip being releasable from said mounting member by releasing said adjustable member from engagement with said strip.

2. In an electric circuit breaker, relatively movable contact members engageable with and disengageable from each other, current responsive means including a thermostatic strip for controlling the disengagement of said contact members, a collar in which a part of said strip is movably positioned, said collar having opposed wall portions, a terminal member having a part disposed between and engaging one of said wall portions and one face of said part of the strip, and means adjustably mounted in the other of said wall portions of said collar and engaging the other face of said strip for releasably securing said strip and said collar to said part of the terminal member.

3. In an electric circuit breaker, relatively movable contact members engageable with and disengageable from each other, an electrical conductor arm mounted for pivotal movement and carrying

one of said contact members, a thermostatic strip having one end thereof releasably engageable with said arm near one end thereof in electrical contact therewith and flexible out of engagement with said arm, an electrical terminal member, said strip having a part in engagement with a part of said terminal member in electrical contact therewith and a part movable toward and away from said part of the terminal member, said strip being mounted so that said end of the strip is movable toward and away from said end of said arm when said movable strip part is moved toward and away from said part of the terminal member, and means mounted for movement and releasably engaging said strip part for holding said strip part in engagement with said part of the terminal member and for adjusting said end of the strip in relation to said end of the arm, said strip being releasable from said terminal member by releasing said adjusting means from engagement with said strip.

4. In an electric circuit breaker, relatively movable contact members engageable with and disengageable from each other, an arm mounted for pivotal movement and carrying one of said contact members, a thermostatic strip having one end thereof releasably engageable with said arm near one end thereof and flexible out of engagement with said arm, a terminal member, said strip having a part in engagement with a part of said terminal member and a part movable toward and away from said part of the terminal member, said strip being mounted so that said end of the strip is movable toward and away from said end of said arm when said movable strip part is moved toward and away from said part of the terminal member, a collar embracing said part of the terminal member, said terminal-member part being positioned between one face of said strip part and an adjacent part of said collar, and a screw adjustably mounted in said collar at a part thereof opposite said first mentioned collar part and engaging the other face of said strip for releasably securing said strip and said collar to said part of the terminal member.

5. In an electric circuit breaker having relatively movable contact members engageable with and disengageable from each other within said casing, an operating member for engaging and disengaging said contact members, said operating member having an axial opening therein, a pin secured to said operating member in said opening and having a part projecting outwardly beyond one side of said operating member, said first mentioned part being knurled and frictionally engaging said operating member in said opening and thereby fixedly secured to said operating member, an arm pivotally mounted on said outwardly projecting part of said pin, one of said contact members being carried by said arm, and an enlarged part on said pin for holding said arm adjacent said side of the operating member.

6. In an electric circuit breaker, the sub-combination comprising an operating member formed of insulation material and adapted to be mounted for pivotal movement, a contact member carried by said operating member in fixed relation thereto, said operating member having an axial opening, a pin passing into said opening axially

of said operating member and having a part projecting from said operating member and a cylindrical head at the end of said last mentioned part, an arm pivotally mounted on said projecting part of the pin at one side of said operating member and held against axial movement by said head of said pin and the adjacent side of said operating member, the other side of said operating member having an integral cylindrical part projecting therefrom in axial alignment with said pin, the part of said pin in said opening being frictionally fixed to said operating member in said opening for preventing axial movement of said pin, and a contact member carried by said arm and movable by the latter into and out of engagement with said first mentioned contact member, said integral cylindrical part of said operating member and said head of said pin providing trunnions for pivotally mounting said operating member.

7. In an electric circuit breaker, a casing, relatively movable contact members engageable with and disengageable from each other within said casing, an operating member for engaging and disengaging said contact members, said casing having a plurality of spaced openings therein, and means integral with said casing internally thereof forming a plurality of passages providing arc chutes leading from the interior of the casing to said openings, respectively, both of said contact members being movable to different spaced positions in said casing in different circuit interrupting positions under different conditions, respectively, one of said arc chutes having its inlet end adjacent the space between said contact members only when they are separated under one of said conditions and another of said arc chutes having its inlet end adjacent the space between said contact members only when they are separated under a different condition.

8. In an electric circuit breaker, a casing having walls defining a chamber, one of said walls at one side of said casing having a bearing recess formed therein, a cover removably secured to said casing and forming a wall of the casing at the opposite side thereof, said cover having a bearing recess in alignment with said first mentioned recess when the cover is secured in said wall-forming position thereof, an operating member positioned between said opposed walls and having parts journaled in said bearing recesses, respectively, companion relatively movable contact members in said casing operable by said operating member for engagement with and disengagement from each other, said casing having interior laterally spaced walls extending between said cover and the wall opposite thereto and defining an arc chute, said laterally spaced walls having free edges which are disposed adjacent said cover when the latter is in said wall-forming position thereof, each of said free edges of said laterally spaced walls having a recess therein, and a terminal member positioned in said recesses and electrically connected to one of said contact members and held in position in said recesses by said cover when the latter is secured to the casing, said terminal member extending across the space between said laterally spaced walls and having a part projecting through said casing to a point at the outerside thereof.

THOMAS M. COLE.
